To all whom it may concern:

Be it known that we, EUSTACE CREEES and CHARLES S. COURT, citizens of the United States, residing at Providence, in the State of Rhode Island, have invented and produced a new and original Design for a Handle for Button-Hooks or Similar Articles, of which the following is a specification, reference being had to the accompanying drawings, forming a part thereof.

the line of graduated beads *h* upon the panel *i* between the scrolls *f f*, and the rows of beads *j j* between the scrolls *f f* and the scrolls *e e*, the ornament *k* between the scrolls *d d*, with the flower *l* at the upper end of a stem *m* arranged centrally of the panel *n* and having the leaves *o o* and *p p* arranged at opposite sides of the stem *m*, the foliated scroll *q*, adjoining the bead *b*, and the series of reversely-curved scroll ornaments *r*.
